UNITED STATES PATENT OFFICE.

WILHELM NEUMANN, OF NEW YORK, N. Y.

SCREW-CUTTING-DIE HEAD.

971,303.

Specification of Letters Patent. Patented Sept. 27, 1910.

Application filed May 10, 1910. Serial No. 560,446.

To all whom it may concern:

Be it known that I, WILHELM NEUMANN, a subject of the German Emperor, and a resident of the city of New York, in the county 5 of Kings and State of New York, have invented certain new and useful Improvements in Screw-Cutting-Die Heads, of which the following is a specification.

The present invention relates to dies used 10 in cutting threads on bolts, pipes and the like.

One of the objects of the invention is to provide a device of this character having a wide range of adjustability, whereby the 15 same will cut threads upon bolts, pipes, etc. of different sizes up to the size of the bore in the die head.

Another object of the invention is to arrange the holders carrying the chasers in 20 such a manner that only a single means is needed for the adjustment of one of the same, the others following automatically the movement thereof.

With these and other objects in view, the 25 invention consists in the construction, arrangement and combination of the several parts hereinafter fully described, pointed out in the appended claims and illustrated in the accompanying drawings, it being understood that many changes may be made in the size, proportion and arrangement of the 30 several parts without departing from the spirit or sacrificing any of the advantages of the invention.

One of the many possible embodiments of 35 the invention is illustrated in the accompanying drawings, in which:—

Figure 1 is a side elevation, partly in section, of a screw cutting die head constructed 40 in accordance with the principle of the invention; Fig. 2 is a front elevation of the same; Fig. 3 is a plan view thereof; Figs. 4, 5 and 6 are plan views of the chaser adjusting blocks, and Figs. 7, 8 and 9 are side 45 elevations of the blocks shown in Figs. 4 to 6, inclusive.

In the drawings, the numeral 10 indicates the shaft to which the die stock 11 is attached. The connection between these two 50 members need not be described here as the same does not form an essential part of the invention, and is, on the other hand, well known in the art. The die stock 11 is provided at its front end with an enlarged 55 head 12, having an axial bore 13, the size of which determines the capacity of the die

head. In the front face of the die head around the axial bore 13 is provided a triangular groove 14 of any suitable cross section, for instance, quadrangular, as shown 60 more particularly in Fig. 1 of the drawings. There are furthermore recesses 15, 16 and 17 provided in the front face of the die stock 11, which are located around the three corners of the triangular groove 14. The 65 purpose of this arrangement will be herein-after described.

The chaser holders 18, preferably three in number, are arranged in grooves 19, 19 of a disk 20, which is fastened by means of 70 screws 21, 21, or in any other suitable manner, to the die stock 11. The holders 18 are, preferably, U-shaped and arranged in similarly shaped radial grooves in the disk 20 in such a manner that the same may be moved 75 in radial directions relative to the bore 13 and the axial bore 22 in the disk 20, which latter bore registers with the bore 13. The chasers 23, 23 are arranged in recesses 24, 24 in the holders 18, and kept therein by 80 means of screws 25, 25. The positions of the chasers upon their holders are determined by pins 26, 26, carried by said chasers and engaging recesses 27, 27 in the holders 18, 18. Obviously the chasers 23 must be 85 provided at their inner ends with cutting edges 28, 28 in the form of screw threads. Each of the chaser holders 18 is provided in its inner leg 29 with a groove 30, which groove is arranged at an angle to the longitudinal axis of said leg. These grooves are 90 engaged by projections 31, 31 of the adjusting blocks 32, 33 and 34, which blocks are slidably arranged in the triangular groove 14, hereinbefore described, and kept in said 95 groove by the disk 20. Each of these blocks is of an oblong configuration and of a cross section which fits into the groove 14. Two of the corners of each block are cut off along the edges 35, 35, whereby the blocks, when 100 placed into the groove 14, form an equilateral triangle. Since the blocks contact with each other along their edges 35, 35, it will be easily seen that when one of these blocks, for instance block 32 is moved in one or 105 the other direction in the groove 14, the blocks 33 and 34 will follow the movement of the block 32 in their corresponding portions of the groove. The projections 31, 31 of the blocks are arranged at an angle to 110 the longitudinal axis of the blocks 32, 33 and 34, and engage as hereinbefore de-

scribed, the walls of the grooves 30, 30 in the legs 29 of the holders 18. As shown in Fig. 2 of the drawings, the axis of the grooves 30 and of the projections 31 coincide.

The means for shifting the blocks 32, 33 and 34 comprises a spindle 36, rotatably mounted in the head 12 of the die stock, and parallel to the longitudinal axis of the 10 block 32. This spindle is screw threaded, as shown at 37 in Figs. 1 and 2 of the drawings. The threads 37 mesh with the threads 38 in the block 32. To facilitate the rotation of the spindle 36, the same is 15 provided with a milled knob 39, and in order to ascertain the amount of the angular movement of the spindle, an enlarged portion 40 thereof is provided with graduations 41, while upon the head 12 a zero mark 42 20 is arranged. A screw 43 in the die stock is adapted to bear against the enlarged portion 40 of the bolt, and to fix the position of the same, if properly tightened.

The operation of the device is as follows: 25 The proper chasers of the required pitch are secured in the manner hereinbefore described upon the holders 18. The holders must then be moved in a radial direction to bring the chasers in the position for cutting a thread of a predetermined diameter. This is accomplished by rotating the spindle 36, whereby the block 32 is moved in a direction of the axis of said spindle, moving thus the holder radially in one or the other 35 direction relative to the axial bore 13, since the projection 31 of the block is arranged at an angle to the longitudinal axis of the same. The blocks 33 and 34 participate in the movement of the block 32 and move 40 thereby their respective holder 18 in a similar manner. As soon as the chasers are in the proper position, the screw 32 is tightened up, whereby the die stock is ready for operation.

45 What I claim is:

1. In a screw cutting die head, the combination with a die stock having an axial bore and a triangular groove around said bore, of a plurality of chaser holders arranged upon said die stock, coöperating adjusting-blocks arranged in said triangular groove and engaging said chaser holders, and means engaging one of said blocks for simultaneously shifting all of the same 50 around said axial bore.

2. In a screw cutting die head, the combination with a die stock having an axial bore and a triangular groove around said bore, of a plurality of chaser holders arranged upon said die stock, contacting adjusting-blocks arranged in said triangular groove and engaging said chaser holders, and means engaging one of said blocks for simultaneously shifting all of the same 55 around said axial bore.

3. In a screw cutting die head, the combination with a die stock having an axial bore, of a disk mounted thereon having a bore registering with the bore of said die stock, a plurality of chaser holders slidably mounted upon said disk in radial directions relative to said bore, coöperating adjusting blocks engaging said chaser holders, and means engaging one of said blocks for simultaneously shifting all of said chaser 70 holders in radial directions relative to said bore.

4. In a screw cutting die head, the combination with a die stock having an axial bore, of a disk mounted thereon having a bore registering with the bore of said die stock and being provided with a plurality of grooves running in radial directions relative to said bore, a plurality of chaser holders slidably mounted in said grooves, coöperating adjusting-blocks engaging said chaser 80 holders, and means engaging one of said blocks for simultaneously shifting all of said chaser 75 holders in radial directions relative to said bore.

5. In a screw cutting die head, the combination with a die stock having an axial bore and a triangular groove around said bore, of a disk mounted upon said die stock having a bore registering with the bore of said die stock and being provided with a 90 plurality of grooves running in radial directions relative to said bore, a plurality of chaser holders slidably mounted in the grooves of said disk, coöperating adjusting-blocks arranged in said triangular groove 95 and engaging said chaser holders, and means engaging one of said blocks for simultaneously shifting all of the same around said axial bores and moving thus said chaser 100 holders in radial directions relative to said 105 bores.

6. In a screw cutting die head, the combination with a die stock having an axial bore and a triangular groove around said bore, of a disk mounted upon said die stock 110 having a bore registering with the bore of said die stock and being provided with a plurality of grooves running in radial directions relative to said bore, a plurality of chaser holders slidably mounted in the 115 grooves of said disk, coöperating adjusting-blocks arranged in said triangular groove and engaging said chaser holders, one of said blocks being provided with screw threads, and a screw threaded spindle meshing with the threads of said block for simultaneously shifting all of the same around said axial bores and moving thus said chaser 120 holders in radial directions relative to said bores.

7. In a screw cutting die head, the combination with a die stock having an axial bore and a triangular groove around said bore, of a disk mounted upon said die stock having a bore registering with the bore of 130

said die stock and being provided with a plurality of grooves running in radial directions relative to said bore, a plurality of chaser holders slidably mounted in the 5 grooves of said disk, contacting adjusting-blocks arranged in said triangular groove and engaging said chaser holders, and means engaging one of said blocks for simultaneously shifting all of the same around said 10 axial bores and moving thus said chaser holders in radial directions relative to said bores.

8. In a screw cutting die head, the combination with a die stock having an axial 15 bore and a triangular groove around said bore, of a disk mounted upon said die stock having a bore registering with the bore of said die stock and being provided with a plurality of grooves running in radial directions 20 relative to said bore, a plurality of chaser holders slidably mounted in the grooves of said disks, contacting adjusting-blocks arranged in said triangular groove and engaging said chaser holders, one of said 25 blocks being provided with screw threads, and a screw threaded spindle meshing with the threads of said block for simultaneously shifting all of the same around said axial

bores and moving thus said chaser holders in radial directions relative to said bores. 30

9. In a screw cutting die head, the combination with a die stock having an axial bore and a triangular groove around said bore, of a disk mounted upon said die stock having a bore registering with the bore of 35 said die stock and being provided with a plurality of grooves running in radial directions relative to said bore, a plurality of chaser holders slidably mounted in the grooves of said disk and being provided with 40 recesses, coöperating adjusting-blocks arranged in said triangular groove having projections engaging the recesses of said chaser holders, and means engaging one of said blocks for simultaneously shifting all of the 45 same around said axial bores and moving thus said chaser holders in radial directions relative to said bores.

Signed at New York, in the county of New York and State of New York, this 23rd 50 day of April, A. D. 1910.

WILHELM NEUMANN.
